UNITED STATES PATENT OFFICE.

JOSEPH WOLFF, OF BROOKLYN, NEW YORK, ASSIGNOR TO SONORA PHONOGRAPH COMPANY, INC., A CORPORATION OF NEW YORK.

RADIO APPARATUS.

Application filed May 27, 1924. Serial No. 716,099.

This invention relates generally to a radio receiving apparatus, and more particularly to an instrument in which radio receiving apparatus and amplifier are combined in the same cabinet. Radio receiving apparatus now in general use utilize an amplifier which is a separate apparatus, apart from the radio receiving apparatus. It is costly; it is large in size, unsightly, occupies considerable space; must be set on the radio cabinet or other convenient place, and is easily and frequently broken. With my invention, I dispense with this unsightly exposed amplifier, and so construct the radio cabinet as to utilize a portion of the interior of the cabinet as an amplifier, and also provide means to deflect the sound in any desired direction.

One of the objects of this invention is to provide an instrument comprising a cabinet having space for a radio receiving set, and for a sound amplifying member provided with a sound passage therethrough and so shaped as to permit a compact arrangement. Radio receiving sets are frequently mounted in the cabinets of phonographs and the phonograph horns are used as parts of the loud speakers of the radio sets. It would, however, in many cases be desirable to have an enclosed radio receiving set and loud speaker independent of a phonograph. I have therefore devised an instrument, comprising a cabinet and a horn to be concealed therein, so constructed that standard radio receiving sets may be placed in the cabinet in compact arrangement with the loud speaker, and that improved reproduction and amplification of sound will be obtained.

Another object of the invention is to provide an improved cabinet, for a combined radio receiving set and loud speaker, which will be simple in construction, economical to manufacture, attractive in appearance, and in which the radio receiving set and loud speaker will be arranged in compact form.

Another object of the invention is to provide a loud speaker horn efficient in operation and so constructed that, when combined with a radio receiving set in one cabinet, a minimum increase in size of the cabinet of the radio receiving set will be required in order to accommodate the loud speaker.

A further object of the invention is to provide a fixed amplifier within a cabinet, and means on the bell portion of the amplifier so that the audio frequency waves can be directed or deflected to any desired place, or so that the waves can be modified if desired.

A further object of the invention is to provide means of the character herein described, simple in construction, thoroughly reliable and efficient for its purpose, positive in operation, and inexpensive to manufacture.

With these and other objects in view to be more fully set forth hereinafter, the invention consists in the novel construction, combination of elements, and arrangement of parts which will be exemplified in the construction hereinafter described in the specification and illustrated in the accompanying drawings considered together or separately.

The inventive idea involved is capable of receiving a variety of mechanical expressions, one of which for the purpose of illustrating the invention, is shown in the accompanying drawings.

The invention will be first described in connection with the accompanying drawings illustrating one embodiment of my invention, wherein similar reference characters are used to designate corresponding parts throughout the several views, and then more specifically defined and indicated in the appended claims.

In the drawings,—

Fig. 1 is a front elevation of a combined radio receiving set and loud speaker illustrating one form of the invention, the door at the mouth of the horn being open.

Fig. 2 is a top plan view of the instrument shown in Fig. 1, the cover being raised to show the interior.

Fig. 3 is a rear elevation, the rear wall being broken away.

Fig. 4 is a sectional side elevation taken on the line 4—4 of Fig. 2.

Fig. 5 is a sectional side elevation taken on the line 5—5 of Fig. 2, the cover being shown in closed position.

Fig. 6 is a front elevation of a radio receiving set illustrating another form of the invention.

Fig. 7 is a top plan view of the instrument shown in Fig. 6, the cover being raised to show the interior.

Fig. 8 is a rear elevation, the rear wall being broken away to show the interior.

Fig. 9 is a sectional side elevation taken along line 9—9 of Fig. 7:

In the embodiment of the invention illustrated in Fig. 1 the instrument comprises a cabinet 10 to accommodate a radio receiving set 11 and a loud speaker 12. The cabinet 10 comprises a rear wall 13, side walls 14 and 15, respectively, a base 16 having feet 17 of rubber or other suitable cushioning material and a front wall 18 spaced from the base 16 to form an opening 19 and provided with a rectangular opening 20 to receive the receiving set 11. The cabinet also comprises a cover 21 connected with the rear wall 13 by hinges 22 and which may be held in raised position, as seen in Fig. 4, by means of a toggle device 23 connected at one end to the side wall 14 and at the other to the cover 21. Provision may also be made of a door 24 hinged to the base 16 and of such dimensions as to close the opening 19 when swung upwardly into position. Preferably the door 24 is provided with a knob 25 to open and close the same. Such door can be utilized to modify the audio frequency waves, if desired, by closing the same.

The receiving set 11 comprises a panel 26 having three dials 27, connected with condensers 29 at the rear of the panel, and two knobs or dials 28, which may control rheostats 28^a for adjusting certain lamps. Projecting rearwardly from the panel 27 and perpendicular thereto is a shelf or support 30 on which are mounted lamp sockets 31 to receive lamps 32. As shown in Figs. 1 to 4, the receiving set may be placed with the shelf 30 resting on side wall 18 below the opening 20 in the said front wall and then fastened in position by screws 33 passing through the panel at its upper and side edges and extending into the front wall 18.

Mounted in the cabinet below and to the rear of the receiving set 11 is the loud speaker 12 comprising a horn 34, a conical portion 35 and a loud speaker device 36 attached to the small end of the conical portion 35 and connected by wires or conductors 37 with a jack or switch 38 beneath the dials 28.

As shown in Figs. 1 to 4, the horn unit has a rectangular mouth and is of such height that it may be inserted into the cabinet from the front below the lower edge of the front wall 18, the mouth of the horn being of such dimensions as to fill the opening 19. The horn 34 comprises parallel upper and lower walls 39 and 40, respectively, and side walls 41 and 42 converging rearwardly to merge with the walls of an opening in a block 43 at the rear of the cabinet.

The block 43 has at its top an opening 44 over which fits the large end of a conical portion 35 which is secured to the block 44 by suitable means such as screws 45.

According to another form of the invention illustrated in Figs. 6 to 9, inclusive, provision is made of a cabinet 46 of greater length than the radio receiving set 11 which may be the same as that shown in the first form of the invention. The cabinet 46 comprises a rear wall 47, side walls 48 and 49, a base 50 having feet 51 of suitable cushioning material attached thereto, a front wall 52 spaced from the left side wall 48 and having an opening to receive the radio receiving set 11. The cabinet 46 is provided with a cover 53 connected with the rear wall 47 by means of hinges 54 and connected with the left side wall 48 by a toggle device 55 to hold the cover in open position, as shown in Fig. 9. The opening at the left of the front wall 52 may be closed by means of doors 56 hinged at their edges to the wall 48 and wall 52 respectively and provided with knobs 57.

In this form of invention, the horn 58 is illustrated as having upper and lower walls 59 and 60 and side walls 61 and 62 converging rearwardly from the mouth of the horn and curved so as to extend to the rear of the radio receiving set 11, which is the same as that shown in Figs. 1 to 5, inclusive, and adjacent the right wall 49 of the cabinet, the small end of the horn being supported in a recess in the upper end of a block 63 resting on the base 50 of the cabinet. Mounted on the small end of the horn is a loud speaker attachment 64, which may be similar to the device 36 shown in Fig. 4, connected to a suitable terminal or jack 65 by means of wires or conductors 66.

As shown in Fig. 7, the shelf 30 is cut away at its left end to accommodate the horn 58.

The doors 56 can be utilized to deflect the audio frequency waves in any direction, or such doors can be used to modify such waves by having the same in closed position. I have found that by enclosing the amplifier in the radio cabinet, I secured greatly improved reproduction, and it is obvious that I have greatly improved the appearance of the apparatus as a whole.

In accordance with the provisions of the patent statute, I have described the principle of my invention, together with the apparatus which I now consider to represent the best embodiment thereof, but I desire it to be understood that my invention is not confined to the particular form of apparatus herein shown and described, the same being merely illustrative, and that the invention can be carried out in other ways without departing from the spirit of my invention, and, therefore, I claim broadly the right to

employ all equivalent instrumentalities coming within the scope of the appended claims, and by means of which the objects of my invention are attained, and the new results accomplished, as herein set forth, as it is obvious that the particular embodiment herein shown and described is only one of many that can be employed to attain these objects and accomplish these results.

Having described my invention, what I claim and desire to secure by Letters Patent is:

1. In a radio cabinet, a rectangular outer casing having a rectangular opening in the front wall thereof, a lintel spanning said opening, said lintel being parallel to the base of the cabinet and spaced therefrom, a resonance box in the bottom of said cabinet having a mouth substantially co-extensive with that portion of the opening in the front wall of the cabinet below said lintel, a radio set baseboard having a vertical control panel at the front edge thereof, said panel forming a closure for the portion of said opening above said lintel when placed in position against the front wall of the casing with said baseboard inside the cabinet.
2. In a radio cabinet, a rectangular outer casing having a rectangular opening in the front wall thereof, a lintel spanning said opening, said lintel being parallel to the base of the cabinet and spaced therefrom, a pair of low, vertical walls converging from the front ends of the cabinet to a point adjacent the central rear portion thereof, said walls having a horizontal cover provided with a circular opening, a conical loud speaker megaphone having a bell secured to said cover with the bell encircling said opening, said walls and said cover delimiting a resonance chamber having an outlet substantially co-extensive with that portion of the opening in the front wall of the casing below said lintel, a radio set baseboard having a vertical control panel at the front edge thereof, said panel forming a closure for the portion of said opening above said lintel when placed in position against the front wall of the casing with said baseboard inside the cabinet.
3. In a radio cabinet, an outer, rectangular casing having a rectangular opening in the front wall thereof and a lintel spanning said opening, said lintel being parallel to the base of the cabinet and spaced therefrom, a pair of low vertical walls converging from the front ends of the said casing to a point adjacent the central rear portion thereof, said walls having a horizontal cover, provided with a circular opening, a conical loud speaker megaphone having a bell secured to said cover with the bell encircling said opening, said walls and said cover delimiting a resonance chamber having an outlet substantially co-extensive with that portion of the opening in the front wall of the casing below said lintel, a radio set baseboard having a vertical control panel at the front edge thereof, said panel forming a closure for the portion of said opening above said lintel when placed in position against the front wall of the casing with said baseboard inside the cabinet.

This specification signed this 21st day of May, 1924.

JOSEPH WOLFF.
